UNITED STATES PATENT OFFICE.

WALTER SCOTT, OF PLAINFIELD, NEW JERSEY.

SHEET-DELIVERY MECHANISM FOR PRINTING-PRESSES.

SPECIFICATION forming part of Letters Patent No. 586,716, dated July 20, 1897.

Application filed March 5, 1894. Serial No. 502,833. (No model.)

To all whom it may concern:

Be it known that I, WALTER SCOTT, a citizen of the United States, residing at Plainfield, in the county of Union and State of New Jersey, have invented an Improvement 5 in Sheet-Delivery Mechanism for Printing-Presses, of which the following is a specification.

The present invention relates to that class 10 of printing-machines in which the paper is drawn from a roll, the web passed through and printed, folded, cut, and delivered.

In printing newspapers two, three, or more webs have been made use of, and these have 15 been run through the printing-machine containing separate presses adapted to print upon each web, as in my Patent No. 467,265, and in such press the webs have been brought together and folded longitudinally. The inclines over which the webs have been passed 20 have in some instances stood in the same direction and in other instances in opposite directions.

In my present improvement the inclines 25 that fold the web longitudinally are placed in the opposite directions, as this is most convenient in associating the printed webs, and I simplify the arrangement of rollers and give greater facility for directing the webs by 30 placing the roller over which two or more of the webs pass so that the side of the roll from which the webs diverge is equidistant from the entering ends of the two folding-inclines that stand in opposite directions, and I combine with this roll a second roll immediately 35 adjacent to the upper end of the folding-incline for guiding the paper as it passes upon such incline, thereby avoiding the necessity of guiding the advancing end of the web of 40 paper through between two closely-adjacent rolls at the ends of the folding-inclines. I also arrange the folding-inclines in such a manner that one of the webs can be split longitudinally and one part pass upon one incline 45 and the other part upon the other incline to be folded with the full-width webs that pass over such inclines, and I fold the webs longitudinally by the action of rolls that flatten the fold without producing creases in the 50 same, and I have discovered that it is advantageous to apply considerable tension to the webs as they pass over the folding-inclines

and between the flattening-rolls in order to prevent the paper forming into creases or puckers, and with this object in view the webs are perforated transversely and a breaking-bar applied to pull the printed product away from the web upon the line of perforations, and the rolls which intervene between the breaking-bar and the folding-incline are 60 made with reference to relieving the pressure upon the folded webs at the moment when the cutting or breaking operation takes place, thereby causing the pull which is applied to the sheets in breaking the folded product 65 away from the web to act upon the web as it lies upon the folding-incline to apply sufficient tension thereto to straighten out the paper properly and reduce the risk of the formation of creases or folds to a minimum. 70

In the drawings, Figure 1 is a diagrammatic view illustrating the present improvement as applied to a printing-machine adapted to print from three rolls of paper. Fig. 2 is an elevation representing the cutters, the breaker-bar, and the rolls acting with the same. Fig. 3 is a modification in the arrangement of the folding devices that may be used with the present printing-machine. Fig. 4 is a diagram illustrating a modification in 80 the drawing-rolls.

The rolls of paper are represented at A A' A², the first plate-cylinders at B B' B², the first impression-cylinders at C C' C², the second impression-cylinders at D D' D², and the second plate-cylinders at E E' E², and I remark that the inking devices for the respective plate-cylinders may be of any desired character and the devices illustrated are of ordinary construction. 90

In the upper press illustrated the web 1 passes over the roll a and down between the first plate-cylinder B and the first impression-cylinder C, beneath such impression-cylinder C, up over the second impression-cylinder D and down between the same and the second plate-cylinder E and around a guide or delivery roll b and beneath the roll d to the rolls of the folding mechanism hereinafter described. 95

In the middle press of the printing mechanism the web 2 from the roll A' passes over the guide-roll a' and between the plate-cylinder B' and first impression-cylinder C', over 100

the second impression-cylinder D' and down between the same and the second plate-cylinder E', below the roller b', and along beneath the roller d' and to the folder.

5 In the lower or third press of this printing-machine the web 3 passes from the roll A², beneath the roll a², up between the first plate-cylinder B² and the first impression-cylinder C², over such impression-cylinder and down 10 below the second impression-cylinder D², and up between the same and the second plate-cylinder E², and over the roll b² and along upon tapes c to the roll d², and thence to the folding mechanism.

15 By the arrangement thus far described it will be observed that the webs 2 and 3 are brought together and supported by the tapes c, and the surface that was printed by the plate-cylinder E² rests upon the tapes c, and 20 the surfaces that have been printed by the plate-cylinders B' B² in giving the first impression are brought together, and in consequence of the distance traveled by the webs before they come together there is but little 25 risk of offset the one on the other, especially in view of the fact that such surfaces have been embossed to a slight extent by the pressure upon the opposite sides of the respective sheets by the plate-cylinders E' and E², and 30 the last impressions upon these webs 2 and 3 coming outwardly are freely exposed to the air, and hence the ink becomes sufficiently set by the time the webs reach the folding mechanism so that there is but little risk of 35 offset when the webs 1, 2, and 3 are associated together and folded longitudinally and 40 cut transversely.

The folding-inclines F and F' are of a width adapted to receive the paper of the webs flat-wise at the upper ends, and they converge to the pairs of folding-rolls G G', so as to fold the webs longitudinally as they are passed down over such folding-inclines, and the rolls 4, 5, and 6 are immediately over one another 45 and parallel with the top edge of the folding-incline F, and the rolls 7, 8, and 9 act to grip the respective webs to such rolls 4, 5, and 6, and it is preferable that the rolls 7, 8, and 9 only act upon the margins of the paper, so as 50 not to press upon the printed portions thereof.

It will be apparent that when the webs 1, 2, and 3 are all brought together and folded upon the incline F the surface of the web 1 which is uppermost in passing to the roll 4 is brought 55 into contact with the surface of the incline F, and the three webs are folded together and pass through between the pair of rollers G to the perforators hereinafter described; but if the printed products are to be separated the 60 web 2 is divided longitudinally by a slitter 12 upon the shaft of the margin-rolls 8, and one half of the web 2 passes over to the folding-incline F' with the web 1, and the other half of the web 2 passes to the folding-incline F 65 with the web 3, and in both instances the half-web comes next to the folding-incline, and hence is carried through by the full-width

70 web, and when the printed webs are thus disposed the half-web 2 passes over a roll 10 at the upper end of the folding-incline F', and the full-width web passes over the same roll 10, but it is advantageous to employ an adjusting-roll 11, which may be raised or lowered to bring the whole and the half web into proper register.

75 In some kinds of printing it is desirable to fold one web longitudinally on the incline F' and to fold two webs longitudinally on the incline F, but by the arrangement before described two webs can be folded on the incline F' and one on the incline F, or the web 2 can be slit longitudinally, and the products passing over the folding-inclines F and F' will occupy exactly the same relation to each other, 80 because the incline F' stands in the reverse direction to the incline F, and the pages will come in the proper relation to each other upon the respective inclines and in the folded products without making any change in the disposition of the forms upon the respective 85 plate-cylinders, because the web 3 is printed by the plate-cylinder B² on the opposite side thereof from the impression given by the plate-cylinder B upon the web 1, and these surfaces of the respective webs come into contact with the folding-inclines F and F', respectively, and the surfaces of these webs that are printed by the plate-cylinders E and E² come uppermost upon such inclines, and the half-web 2, (when said web is slit longitudinally,) that comes upon the folding-incline 90 F', is beneath the same pages that the other half of the web is beneath upon the incline F, it being understood that for two similar products the same matter is to be printed upon 95 the webs 1 and 3 and printed in duplicate upon the web 2.

100 It is advantageous to separate the folding devices, as represented in Fig. 1; but if the folding-inclines are brought closely together, 105 as represented in Fig. 3, the sheets will be associated in exactly the same manner as before described and will be passed off between the pair of long folding-rolls G² in substantially the same manner as they will be between the pairs of shorter folding-rolls G and G'. In this case it is only necessary to employ a guide-roll 13 over the folding-incline F' instead of using the rolls 10 and 11.

110 In both of the arrangements represented 110 the sides of the rolls 5 and 4 over which the webs pass are in line with the upper end of the folding-incline F, and hence the webs passing to that folding-incline F from one or both rolls are free and unobstructed, so as to 115 be easily guided by the pressman, and when the rollers are arranged as shown in Fig. 3 the upper ends of the inclines F and F' are equidistant from the point of contact of the webs with the roll 5, so that the webs can be carried from that roll to either of the inclines 120 without changing the adjustment and without obstruction due to numerous guiding-rolls that have heretofore been necessary, and 125 130

in this Fig. 3 the web 2 is represented as slit longitudinally and one half passed to the incline F and the other half to the incline F', and the web 1 is shown as passing over the 5 roll 4 and the web 3 as passing over the roll 6, but two or all of the webs can be passed over the roll 4 or 5 and be led to the folding-inclines F and F', or either of them, as the register of the webs will not be disturbed by 10 changing from one incline to the other, because the contact of the web with the roll is directly over the apex of the inclines.

The devices hereinafter described are substantially the same when used with short rolls 15 and with separate folding devices, one for each folder F F', as they will be when made longer, so as to correspond in length with the roll G², to act upon the two longitudinally-folded webs or products; but, as before intimated, it is advantageous to make use of 20 separate folders and the rolls and cutters associated therewith, so as to more readily adjust the folding and cutting devices in bringing them to the proper register. This arrangement, as represented in Fig. 1, allows 25 for the folders to be run entirely separate. Hence they only require adjustment to act in harmony with the webs as they reach such folding devices instead of having to adjust 30 the webs to bring them to the proper position for being simultaneously folded by one folding mechanism, as in Fig. 3. In Fig. 2 I have represented the rolls and devices that act with the folding-incline F, such devices being 35 duplicated to act with the folding-incline F' or made longer, so as to act upon both folded webs.

The rolls of the pair of rolls G, located at the apex of the folding-incline F, are made 40 conical adjacent to the fold in the web, so that pressure is not applied by such rolls G directly to the fold; but the fold is free to draw over the point of the incline F, which point is preferably slightly below the plane 45 passing through the axes of the rolls G, and it is advantageous to keep these rolls G at a slight distance apart, so as not to apply pressure to the paper as it passes through between them, but the rolls H are set sufficiently close 50 together to act as drawing-rolls in pulling the paper of the web along over the incline F and passing the same down to the perforating-cylinders I, which latter perforating-cylinders are of usual character, one having a blade of 55 points and the other a groove into which such points pass, thereby making a line of perforations transversely of the printed and folded webs, and after the webs have been thus folded and perforated they pass between the 60 rolls 15 and 14, over which pass the tapes or belts 16 and 17, the tapes 16 passing around a roll 18 and the tapes 17 passing around a roll 19, having a breaker-bar 20, which breaker-bar may be constructed and operate substantially the same as that represented in Letters 65 Patent No. 484,251, granted to me October 11, 1892.

The rolls H are grooved longitudinally and geared together in such a manner that the longitudinal grooves coincide for a greater or less portion of the revolution of the rolls. Hence when these longitudinal grooves coincide the tension upon the paper is momentarily relieved and the cutting-cylinders do not grip the paper. Neither do the rolls G nor the 70 rolls 14 and 15, and the parts are so proportioned that at the moment the breaker-bar 20 grips the paper against the roller 18 with an accelerated movement, so as to break the sheets away from the web upon the line of 80 the transverse perforations, the longitudinal grooves in the rolls H coincide, so that the tension, which is considerable, that is applied by the breaker-bar to the folded sheets in breaking them away from the web applies a 85 pull to the webs as they lie upon the folding-incline, and hence the webs are exposed to a tension that extends back to the upper ends of the folding-inclines, and the webs are drawn out straight and any wrinkles are removed or any tendency to pucker or run untrue compensated, and the webs are made to 90 register by the tension drawing out any slackness in either web.

By this improvement a great benefit is obtained in insuring the proper movement of the webs through the press, because the pull acts upon every folded product as separated and effectually rectifies any tendency to irregularity in the movement and the paper is not thereby injured, because it possesses more or less elasticity, and any frictional detention that may arise at one part or upon one web is compensated so as to maintain the register of the respective pages as they are brought together in folding and cutting the webs. 95

If it is desired, larger rolls H may be made use of, each having two grooves, so as to relieve the grip upon the folded webs twice in each revolution, as illustrated by the diagram, Fig. 4, instead of once each revolution, as represented in Fig. 2.

The webs folded longitudinally, associated together as before indicated, and perforated and separated as described may be delivered 115 in any desired manner. I have represented an imposing-cylinder K, with belts f passing around the same and around the roll 19 and over the rolls 21 22 and beneath the rolls 23 and 24, the latter of which is preferably a 120 tightener, and the belts g pass around the rolls 25 and 26, and there is a binding-roll 27, acting in connection with guides 28 to keep the associated sheets together as they may be held by the grippers 29 upon the imposing-cylinder K, so as to bring two or more printed 125 products together before delivering them at the roll 25 and between the belts f and g, by which they are conveyed to any suitable folding mechanism, but this part of the apparatus may be dispensed with and the longitudinally-folded webs pass from the breaker-cylinder 19 to any suitable folder. 130

In Fig. 4 I have represented rolls o at the

edges of the folding-incline F, which rolls o are driven by gearing p at a surface speed slightly faster than the speed of the web of paper passing over such folding-incline F.

- 5 These rolls aid in applying a slight tension to the web of paper as it passes over such folding-incline, and it is advantageous to apply in the surfaces of each roll a helical groove similar to a screw-thread to spread the paper 10 and prevent the formation of wrinkles in the paper as it passes over the incline, and these rolls are also advantageous because they lessen the tendency to blur or rub the ink in passing around the edges of the folding-incline, because the surface speed of such rolls approximates the surface speed of the paper itself.

It is generally advantageous to relieve the gripping action of the drawing-rolls H twice 20 for each rotation of the perforating-cylinders, in order that the gripping action may be released at the time the perforators pass into the paper, and hence said perforators will apply a tension to the paper when the paper is 25 free to be acted upon as it passes over the folding-incline, as well as when the breaker-bar 20 acts upon the folded web or product to pull the same away from the advancing end of the web at the perforations. Thereby 30 there are two forces applied to the web of paper of each product that is delivered.

If one web is under greater tension than the adjoining web, the sheet is separated from said web first by the action of the breaker-bar, and instantly thereafter the separation takes place at the line of perforations in the web which is slack. Thereby the slack web is the last one pulled up, which takes place during the time that the tighter web has the 40 opportunity to slightly contract, and in this manner the constant equalization is going on once for each product delivered as the same is broken away from the web, and this is in addition to the pull before mentioned which 45 results from the action of the perforators at the time when the drawing-rolls H cease their hold upon the folded webs.

I remark that the pulling action of the drawing-rolls H may be relieved or lessened, 50 for the purposes aforesaid, by flattening one or both rolls or by grooving them, as aforesaid, or by automatically lessening the force by which they are pressed toward each other in any suitable manner.

55 In printing-machines of the character hereinbefore described I have found difficulty in regulating the tension applied to the web as it is passed through the printing-press, because as the web lessens in diameter as the 60 web is pulled off the leverage of the web against the friction detaining device applied to the roll lessens. I therefore apply to the web an automatic tension-regulator for lessening the tension according to the diameter 65 of the roll, and with this object in view the clamps D D' are applied to the friction-wheel C, that is upon a shaft or arbor passing through

and connected with the paper-roll A, and there is a lever R, provided with a cam, that acts against one end of the clamping-segment D', the other end of such clamping-segment D' being connected by an adjusting-screw with the clamping-segment D, which latter is attached at its lower end by a stud to the frame of the printing-press, and the lever R' 70 has a block 9^x at its outer end, which rests against the surface of the paper of the roll A², and there is a spring or weight 10^x for turning the lever R' and pressing the block 9^x toward the roll, and the rod 8 connects the 80 lever R' to the lever R, and this rod is adjustable by a slot in the lever R, so as to vary the action of the levers R and R' in applying greater or less pressure from the cam to the clamping-segment D', and the pressure and 85 friction are relieved or lessened automatically as the roll of paper becomes smaller as the web is drawn off.

It will be apparent that the rolls H may be 90 adjusted so that the grooves coincide accurately, and hence the pull will be relieved only during the time that the grooves coincide, but if one groove is slightly in advance of the other the time during which the hold will be relieved is increased, and only one 95 roll may be grooved instead of both, and a flat surface on the roll will answer the same purpose as a groove and be the equivalent of the same.

In cases where I have before employed rolls 100 and a folding-incline, the apex of which is below a plane passing through the axes of such rolls, the ends of the rolls have been behind or back of the folding-incline.

In the present device the ends of the rolls 105 G at the sides of the apex of the incline are conical, as aforesaid, and I find that the conical surfaces keep the fold toward the apex of the incline in such a manner as to insure a perfect longitudinal fold without the risk 110 of tearing the paper or forming creases or wrinkles, and this result appears to be effected in consequence of the conical ends of the rolls coinciding with the shape that the paper web assumes as it is being drawn along 115 over the apex of the incline.

In printing-presses such as shown in my Patent No. 558,424, where the guide-rolls have straight ends or are turned down to a smaller diameter, as represented in Fig. 6 of said patent, and when the web is running tight or with a normal tension, the point of the longitudinal folder within the fold of the paper keeps such paper in its proper condition for the fold to be made in line with the said point 125 by the drawing-rolls, but should the web become loose the apex of the folding-incline does not fully distend the fold in the paper and it is liable to run through with false folds or creases, resulting from the looseness of 130 the paper or from coming into contact with the angular portion of the roll, but where the ends of the roll are made conical, as in the present improvements, the paper is kept in

the form of a narrow loop, which is by the rolls pressed toward the place where the single fold is ultimately given in the paper by the drawing-roll, thus avoiding the false folds or creases which have sometimes been made, 5 in the manner before indicated.

I claim as my invention—

1. The combination in a printing-machine, of two presses for printing upon separate webs 10 and forwarding such webs in one general direction and in a flat condition, a roll over which such webs pass, two folding-inclines having converging edges and standing in opposite directions, a roll adjacent to the receiving end of each incline between which rolls and the inclines the webs of paper pass, the side of the roll from which the webs diverge in passing to the inclines being over and equidistant from the entrance ends of 15 such inclines, so that the webs of paper can be passed in either direction without throwing the printed matter out of register, substantially as set forth. 75
2. The combination in a printing-machine, 25 of two presses for printing upon separate webs and forwarding such webs in one general direction and in a flat condition, a roll over which such webs pass, two folding-inclines having converging edges and standing in opposite directions, a roll adjacent to the receiving end of each incline between which rolls and the inclines the webs of paper pass, the side of the roll from which the webs diverge in passing to the inclines being over 30 and equidistant from the entrance ends of such inclines, so that the webs of paper can be passed in either direction without throwing the printed matter out of register, guide 35 and drawing rolls for drawing the folded webs over both inclines, and cutters or perforators 40 acting simultaneously on both folded webs, substantially as set forth. 80
3. The combination in a sheet-delivery mechanism, of a folding-incline, revolving 45 perforating-cutters, forwarding rolls between the folding-incline and the perforating-cutters, one of such forwarding-rolls having a longitudinal depression for liberating the pull upon the folded web periodically, and a 50 breaker-bar acting to pull the perforated sheets or product from the web when the forwarding-rolls cease their hold upon the same for applying a tension to the web upon the 55 longitudinal incline for straightening such web and maintaining uniformity in the delivery of the product, substantially as set forth. 85
4. The combination with a folding-incline for folding a web of paper longitudinally, of rolls adjacent to the apex of the folding-incline, such rollers being cylindrical, except at the end portion closely adjacent to the apex of the incline where such rolls are 60 conical for guiding the paper near the fold, and forwarding-rolls for applying tension to the 65 web of paper after the same has passed the folding-incline and its rollers, substantially as set forth. 90
5. The combination with a folding-incline, of rollers at the edges of the incline, and gearing for driving the same at the surface speed 70 or nearly so of the paper, forwarding-rolls for acting upon the web after the same has been folded, and perforating-rolls for perforating the web transversely, substantially as set forth. 75
6. The combination in a sheet-delivery mechanism, of a folder for folding the web of paper longitudinally, forwarding-rolls with a longitudinal depression for releasing the grip upon the folded web periodically, mechanism for perforating the web transversely, and a breaker-bar acting to apply tension to 80 separate the sheet or sheets at the line of perforations from the web and to apply a tension upon the web as it passes over the longitudinal folding mechanism, substantially as set forth. 85
7. The combination in a sheet-delivery mechanism, of a folder for folding the web of paper longitudinally, forwarding-rolls with a longitudinal depression for releasing the grip upon the folded web periodically, mechanism for perforating the web transversely, 90 a breaker-bar acting to apply tension to separate the sheet or sheets at the line of perforations from the web and to apply a tension upon the web as it passes over the longitudinal folding mechanism, rollers and belts or tapes for conveying the perforated web from the perforator to the breaker-bar, substantially as set forth. 95
8. The combination with the folding-incline over which the paper passes and is folded longitudinally, of a perforating device and drawing-rolls acting intermittently upon the web 105 to apply tension to the same and to liberate or lessen the hold of such drawing-rolls upon the web while the perforating devices are acting upon the web to apply tension to the same, substantially as set forth. 110
9. The combination with the folding-incline, of drawing-rolls acting intermittently upon the folded web of paper, a perforating device and a breaker-bar acting to separate the product from the web at the time the drawing-rolls cease to act upon the web, substantially 115 as set forth. 110
10. The combination in a folding and sheet-delivery mechanism, of an incline over which the web is folded longitudinally, perforating 120 mechanism and a breaker-bar, drawing-rolls between the folding-incline and the perforating mechanism, such drawing-rolls acting automatically and intermittently to liberate their hold upon the folded web during the perforating operation and during the breaking operation, substantially as set forth. 125
11. The combination with the axis for the web or roll of paper, of a friction-wheel and friction mechanism acting upon the wheel, 130 the lever R' and block resting upon the surface of the roll of paper, a cam for acting upon the friction-clamp, and a connection therefrom to the lever R', whereby the fric-

tion applied to detain the web as drawn from the roll is automatically regulated according to the size of the roll of paper, substantially as set forth.

5 12. The combination with the folding-incline and the roll over which the web of paper passes to such incline, of converging rolls at the edges of the incline, bevel-gearing and a shaft by which such rolls receive a rapid rotary movement as the paper passes around such rolls and is folded, substantially as set forth.

13. The combination with the folding-in-

cline over which the web is folded longitudinally, of two rolls for acting on the folded web, such rollers having conical ends that are closely adjacent to and support the paper as it passes from the apex of the folding-incline, substantially as specified.

Signed by me this 26th day of February, 1894.

WALTER SCOTT.
